US00D706357S

(12) **United States Design Patent**
Ashida et al.

(10) **Patent No.:** US D706,357 S
(45) **Date of Patent:** ** Jun. 3, 2014

(54) **ELECTRONIC COMPUTER**

(71) Applicant: **Nintendo Co., Ltd.**, Kyoto (JP)

(72) Inventors: **Kenichiro Ashida**, Kyoto (JP); **Masato Ibuki**, Kyoto (JP); **Shinji Yamamoto**, Kyoto (JP); **Fumiyo Yoshi Suetake**, Kyoto (JP); **Akiko Suga**, Kyoto (JP); **Naoya Yamamoto**, Kyoto (JP); **Hitoshi Tsuchiya**, Kyoto (JP); **Junji Takamoto**, Kyoto (JP); **Noboru Wakitani**, Kyoto (JP); **Yasuhisa Kitano**, Kyoto (JP); **Toshiaki Iwao**, Kyoto (JP); **Yuji Hori**, Kyoto (JP); **Takafumi Nishida**, Kyoto (JP); **Hiroki Ikuta**, Kyoto (JP)

(73) Assignee: **Nintendo Co., Ltd.**, Kyoto (JP)

(**) Term: **14 Years**

(21) Appl. No.: **29/454,949**

(22) Filed: **May 15, 2013**

Related U.S. Application Data

(62) Division of application No. 29/407,696, filed on Dec. 1, 2011, now Pat. No. Des. 684,916.

(57) **CLAIM**

The ornamental design for an electronic computer, as shown by and described.

DESCRIPTION

FIG. 1 is top, front and left perspective view of an electronic computer showing our new design;

FIG. 2 is a bottom, rear, and right perspective view thereof;

FIG. 3 is a top plan view thereof;

FIG. 4 is a bottom plan view thereof;

FIG. 5 is a front view thereof;

FIG. 6 is a rear view thereof;

FIG. 7 is a left side view thereof; and,

FIG. 8 is a right side view thereof.

Subject matter shown in dashed lines is for reference purposes only and forms no part of the claimed design.

1 Claim, 1 Drawing Sheet
